United States Patent Office

Des. 192,237
Patented Feb. 13, 1962

192,237

POWDER PUFF OR THE LIKE

Del Schmidt, New York, N.Y., assignor to Cheramy, Inc., New York, N.Y.

Filed Mar. 1, 1961, Ser. No. 64,111

Term of patent 3½ years

(Cl. D86—10)

Fig. 1.

Fig. 2.

Fig. 3.

FIG. 1 is a top view of a powder puff or the like showing my new design;

FIG. 2 is an end view thereof; and

FIG. 3 is a side view of the same.

The side opposite to FIGURE 1 (the back view of the powder puff) is plain.

I claim:

The ornamental design for a powder puff or the like, as shown.
